UNITED STATES PATENT OFFICE.

CONRAD F. BARTLING, OF GREENVILLE, OHIO.

FENCE-MACHINE.

SPECIFICATION forming part of Letters Patent No. 392,981, dated November 20, 1888.

Application filed September 26, 1887. Serial No. 250,688. (Model.)

To all whom it may concern:

Be it known that I, CONRAD F. BARTLING, a citizen of the United States, residing at Greenville, in the county of Darke and State of Ohio, 5 have invented a certain new and useful Improvement in Fence-Machines, of which the following is a specification.

My invention relates to that class of fence-making machines by means of which a fence is formed by twisting wires on either side of vertical palings or pickets, and has particular relation to the improvement of my former invention, for which Letters Patent No. 350,967, under date of October 19, 1886, were granted 15 me.

The objects of my invention are to provide an adjustable support for the twisting-post above the proposed line of fence and to so connect said post and support as to admit of the former being made to travel backward and forward on the latter, thereby obviating the difficulty usually experienced in forming a ground-track; to combine with said elevated support an adjustable guide-plate adapted to 25 be made to travel and bear on the upper ends of the pickets; to so construct the twisting-tube as to admit of the entrance therein of the waste oil from the tube-boxing, and to admit of the passage therethrough of any enlargement 30 of the wire, such as may be caused by a connection of two wire ends; to form adjustable bearings for the vertical portion of the operating-lever; to attach to said operating-lever two or more picket-pushing arms; to 35 provide a suitable wire-coupling device; to provide the stretching or tension post with adjustable tension-plates; to form a suitable wire-holding reel, and to so construct my improved fence-making machine as to greatly facilitate 40 the manufacture of fencing. These objects I accomplish in the manner illustrated in the accompanying drawings, in which—

Figure 1 is a perspective view of my improved machine in position for use. Fig. 2 is 45 a front elevation of the same. Fig. 3 is a plan view of the wire-reel. Fig. 4 is a vertical section of the same. Fig. 5 is a plan view in detail of a picket-pressing arm detached. Fig. 6 is a plan view of one of the adjustable bearing-arms for the operating-lever. Fig. 7 is an 50 end view of said bearing-arm. Fig. 8 is a plan view of the stretching-post, showing tension-

plate and wire-separator. Fig. 9 is an end view of the tension-plate. Fig. 10 is an end view of one of the twister sprocket-wheels. 55 Fig. 11 is a side elevation of the same, showing the twister-tube. Fig. 12 is an enlarged view of the remaining end of the tube, showing the operating-crank connected therewith. Fig. 13 is a side view of the picket top plate 60 and its connecting-arm, and Fig. 14 is a front view of the same.

Similar letters refer to similar parts throughout the several views.

A represents the twisting-post, which, being supported, as hereinafter described, above the ground, extends upward to a point at the desired height above the proposed fence.

B represents a horizontal track-bar, forming a track and made to extend above the line 70 of the fence-top, in which position it is supported by means of front and rear stay-arms, b' b b. The arm b' is pivoted to the front end of the track, while the arms b b are made to straddle the line of the fence, being inclined 75 toward each other at the top, and pivoted one on each side of the remaining end of the track, as shown in Fig. 1 of the drawings. These stay-arms have their lower ends resting on or inserted in the ground.

a represents a vertical wheel bearing-arm or post-extension having its lower end secured to the upper portion of the twisting-post, and having journaled to its upper portion a grooved track wheel or roller, a', the latter being, as 85 hereinafter described, made to bear and run on the track B.

Loosely inclosed within suitable metallic boxing-plates, C, the latter being secured at desired points on one side of the twister-post, 90 are metallic twisting-tubes c, each of the latter having formed therewith on its front end a sprocket-wheel, c'. Each of the twisting-tubes is provided with two horizontal partition-plates, c², and a vertical central connecting-bolt, c⁴, and has a horizontal slotted opening, c⁵, in each of its sides, as shown in Figs. 11 and 12 of the drawings.

The front end of the twister-tube is closed, with the exception of two oppositely-located 100 openings or eyes, c⁶, which communicate, respectively, with the compartments of the tube formed by the partitions c². Made to project forwardly from the front side of the twister-

post at points, respectively, beneath and above the upper and lower twister-tubes are oblong lever-bearing arms D, each of which is provided with upwardly-flanged sides, one of said sides 5 being provided with teeth to form a rack, d. Above the upper and beneath the lower one of these bearing arms is secured, as herein-after described, a picket-pressing arm, E, having one or more perforations, e, a short open 10 slot, e', in its rear end, and a partially hook-shaped projection, e'', formed on its front end. Said picket-pressing arms are rigidly secured in their positions above and below the bearing-arms D by means of the vertical portion 15 of an operating-lever, F, which passes through one of the perforations e of the upper one of said picket-pressers, to which it is keyed or otherwise secured. It then passes loosely through a central opening in a small bearing-block, d', the latter having on one side there-of teeth d'', and being of such shape as, when seated, as shown, between the flanged sides of the arm D, to cause its teeth to interlock with those of the rack d, and to bring its upper 20 surface flush with the upper side of said arm, and thence through the block d'. The lever-rod is continued downward and connects in a similar manner the lower picket-presser and bearing-arm, terminating in an outward bend, 25 as shown. Immediately above the upper picket-pushing arm the lever-rod is also bent outwardly to form a lever-handle, f.

f' represents a vertical shifting-bar having projecting from its inner side, at two or more 30 points corresponding with the positions of the wire strands used in forming the fence, notched lugs f''. This shifting-bar is provided on its outer side with two laterally-projecting metallic arms, f'', said arms being pivoted, respectively, to the upper and lower picket-pressers and lever-arms by means of pivot-bolts f', made to pass vertically through the outer ends of the arms f'' and into the slots e' of the picket-presser arms E.

45 H represents a metallic arm bolted to and depending from the track B, near the front end of the latter.

h represents a sliding guide-plate having lateral flanges and a flaring mouth at its rear end 50 to facilitate its passage upon the top of the pickets. This flanged guide-plate is adapted to be made to fit loosely and slide over the tops of the pickets, embracing two or more of the latter at a time, and is provided on one 55 side with an outwardly-projecting pin, h', having an elongated head running in the direction of the length of the plate. An adjustable connection is formed between the guide-plate and vertical arm H by turning the said plate to a 60 vertical position, inserting the pin h' through the desired one of a vertically-arranged row of elongated openings, H'', formed in the arm H, and then lowering the plate until in its proper position on the pickets.

65 G represents an endless chain belt, which, as shown in Fig. 2 of the drawings, passes over and engages with the teeth of the sprocket-

wheel c'. Motion is communicated to said sprocket-wheel by means of a crank-arm, I, having at its front end two diverging curved 70 fingers, i, adapted to partially embrace the rear projecting end of the upper twisting-tube, c, to which said fingers are secured by set-screws or otherwise.

J represents my improved wire-feeding reels, 75 one of which is mounted loosely on each side of the center of a horizontal shaft, J', said shaft being supported at its center by means of a vertical arm, J'', having an elongated base, J'', which rests upon the ground. Each of said 80 reels consists of four or more circular wheels or rings, K, having a number of flattened spokes, k, which are bolted at their inner ends to a flat disk or hub, k', the latter being mounted 85 loosely on the shaft.

At equidistant points on each of the spokes k are formed perforations k'', said perforations being designed to receive horizontal rods k''. Said rods, being passed through corresponding holes in each of the spokes of a reel, form, as 90 will be seen, a circular frame between each of the reel-bands, on which is placed, as herein-after described, the wire to be used. This double reel is placed at the desired distance from the twisting-post and on the proposed 95 line of fence. In Fig. 1, the reels being represented in perspective and on a smaller scale than in Figs. 3 and 4, the dividing-arms of each spool of said reel have not been shown, to prevent confusion of lines.

100 Between the reels and twisting-post is located a vertical stretching or tension post, L. The ends of the wires m running from the reels (on which there are preferably six coils) extend forwardly in pairs, each pair of wires 105 being held against one side of the stretcher-post, as herein-after described, at points respectively opposite the twisting-tubes, from which points they extend forward and pass through said twisting-tubes, one wire through 110 each compartment m', and pass out through the eyes c'.

115 l represents the tension-plates, each consisting of a metal plate having a central bolt-hole, and having its inner surface provided with two shallow grooves, between which at the rear end of said plate are made to project binding-lugs l'. A bolt, l'', is made to pass through the central bolt-hole of the plate and thence through the post L, the head of the 120 bolt bearing on the center of the plate, and a nut on its outer end holding it in place and regulating the tension of the wires, while the lugs l' of the plate bear against the rear side of the post and relieve the bolt l'' of lateral strain. 125 Each pair of wires from the reel is made to pass between one of these plates and the tension-post, or between the plate and a washer or metallic collar, which may be made to surround the bolt and bear against the post. A 130 similar collar may also be located between the bolt-nut and post.

A wire-coupling device, N, consisting of two or more metal collars, is made to bear on

opposite sides of the wires by means of a central bolt made to pass through said collars and between the wires. The purpose of said coupling is to secure together the two wires of a strand and cause them to pull with the same tension upon the reels of wire.

In order to prevent the sagging of the wire, stretching chains or ropes are attached to the post L, and from thence extend to the vertical frame-arm J² of the rail to which it is attached, and thence to a stake, P, driven in rear of the reel.

The operation of my device is as follows: All of the bands or wheels being removed from the reel-shaft, except the two which are adjacent to the vertical frame-arm J², and the horizontal rods k³ being inserted through the desired holes in said wheel-spokes, a bundle of wire is slipped over each set of said rods and the next dividing-wheel placed in position on the rods, said operation being continued until the reel is completed. The reel is then placed on the proposed line of fence adjoining or near the twisting-post, the latter being suspended, as described, at a point adjacent to the first post. The ends of the wires from the reel are then threaded in pairs through the respective twisting-tubes, one wire through each compartment m', and thence out through the eyes c⁵, thence around the first post, where the ends of each pair of wires are united. The reel is then wheeled back to the desired distance and the tension-post placed in position. One or more turns of the twisting-tubes are then given by means of the crank-arm I, thus causing the wires to be twisted together in rear of the post. A picket is then inserted vertically between the wires, the twisting-post moved slightly forward, (the track-wheel a' traveling on its track B,) and the same number of turns given the twister as before, although in the opposite direction. Two pickets having been placed vertically true in this manner, the third picket is then inserted between the wires and the shifting-bar f' swung toward the fence, its notched lugs f² being made to engage with the twisted wires between the last two fast pickets to form a leverage for the lever-handle f, which is then pushed back, causing the twisting-post to move forward and the hooked ends c² of the picket-pressing arms to press the picket about to be secured into a vertical position firmly against the last twists. The crank-arm may again be turned, as described, the shifting leverage-bar released and placed between the last two fast pickets, and the operation repeated. Meanwhile the wires used are escaping from the reels, and are held with the desired degree of tension by means of the tension-plates l, and are compelled to pull through the tension-plates evenly by means of the coupling device N. When two pickets have been secured in place, the arm H, depending from the track B, is secured, as before described, to the guide-plate h at the desired height. The guide-plate h, besides forming a level to regulate the upward extension of the pickets, serves as a

support for the track, the stay b' being released from the ground after the fence is started. The height of the fence is indicated by means of a pin, s', projecting from the desired hole in a picket-gage, s, the latter consisting of a vertical perforated bar having a rearwardly and slightly forwardly extending arm projecting from its rear edge and supported between the upper portion of the upper boxing-plate and the side of the twisting-post.

It will be observed that the slots c³ of the twisting-tubes will admit the waste oil from the boxing onto the wires, which, as is well known, will greatly decrease the friction on the wires when being twisted. It will also be seen that the lever-bearing blocks d' may be seated at any point within their bearing-arms, thus making the lever-rod adjustable, as may be desirable, in changing the space between pickets.

When it is desired to change the position of the reels, the base J³ may be raised until at right angles with the position above described, thus letting the wheels or bands drop to the ground and admitting of the reel being wheeled to the desired position, which, as will be seen, will cause the wire to unwind from the reel.

Having now fully described my invention, what I claim, and desire to secure by Letters Patent, is—

1. In a fence-machine, the combination of the twisting-post A, having the extension a and track-roller a' thereon, with the elevated track B, an inclined stay, b', carrying said track at one end and two inclined stays, b, at the other, the latter stays being united together at the top and straddling the line of fence, substantially as and for the purpose described.

2. The combination, with the elevated horizontal track B, supported as described, of the vertical arm H, bolted to said track and to a horizontal guide-bar, h, adjustably secured thereto and adapted to rest and slide on the picket-tops of a fence, substantially as and for the purpose specified.

3. The combination of the twisting-post suspended as described, the flanged bearing-arms D, having racks d and adjustable bearing-blocks d', with the double-armed lever F, pivoted therein, and the picket-presser E, substantially as and for the purpose specified.

4. The combination, with the twisting-post suspended as described, the flanged bearing-arms D, having racks d and adjustable bearing-blocks d', of the double-armed lever F, carrying picket-pressers E, and the vertical shifting-bar f', pivotally connected with the lever-arms and picket-pressing arms and having notched projections f², substantially as and for the purpose specified.

5. The combination of the twisting-post suspended as described, the flanged bearing-arms D, having racks d, adjustable bearing-blocks d', and picket-gage s, with the double-armed lever F, carrying picket-pressers E, and the

vertical shifting-bar f'' , pivotally connected, as described, with the lever-arms and picket-pressing arms, and having notched projections f'' , substantially as and for the purpose specified.

6. The combination of the tension-post L and its adjustable tension and guide plate l , having laterally-projecting lugs l' , with the wire-coupling device N , consisting of a bolt and 10 collars, the latter made to embrace the wires forming a strand on each side of said bolt, substantially as and for the purpose specified.

7. In a feed-reel for fence-machines, the combination of the supporting frame $J^2 J^3$ with 15 the shaft J' , the separating bands or wheels K , and perforated spokes k , connected by means of removable reel-rods, substantially as described.

8. In a fence-machine, the combination of 20 the twister-post movably supported, as described, with the twisting-tubes, their sprocket-

wheels, connecting-belt, and crank-arm I , said tubes being supported, as described, on said post and provided with horizontal slots c^3 and connecting-partitions c^2 , substantially as and 25 for the purpose specified.

9. In a fence-machine, the combination of the vertically-suspended twisting-post, the divided and slotted twisting-tubes, their sprocket-wheels and connecting-belt, double-armed 30 operating-lever, lever-bearing arms having adjustable bearing-blocks, picket-pressing arms, pivoted shifting leverage-bar having the notched projections, stretching-post, tension-plates, and wire separators and reels, all constructed and arranged substantially as and for 35 the purpose specified.
